UNITED STATES PATENT OFFICE.

ALBERT BROADMEYER, OF HARRISBURG, PENNSYLVANIA, ASSIGNOR TO THE W. O. HICKOK MANUFACTURING COMPANY, OF HARRISBURG, PENNSYLVANIA, A CORPORATION OF PENNSYLVANIA.

SHEET-FEEDING MECHANISM.

Application filed June 13, 1927. Serial No. 198,550.

The present invention relates to sheet feeding apparatus, particularly sheets of paper, card-board and the like, and the object is to provide novel mechanism of a simple character, by which the top of the pile of sheets may be maintained at a constant level, irrespective of the speed at which the sheets are removed.

In the accompanying drawings the mechanism is shown as part of an interleaving apparatus that constitutes the subject-matter of a companion application. It is to be understood, however, that the mechanism is not limited to such use.

Figure 1 is a side elevation of such an embodiment of the invention,

Figure 2 is a view in elevation of the opposite side,

Figure 3 is a top plan view,

Figure 4 is a longitudinal sectional view on the line 4—4 of Figure 3,

Figure 5 is a sectional view on the line 5—5 of Figure 4,

Figure 6 is a view in elevation of the ratcheting mechanism,

Figure 7 is a sectional view on the line 7—7 of Figure 6,

Figure 8 is a vertical cross sectional view,

Figure 9 is a detail view of the pawl carrier and detent, showing the latter in its operative position and with the operating link at one end of its throw.

Figure 10 is a view similar to Figure 9, but with the operating link at the opposite end of its throw.

In the structure disclosed, a suitable frame 11 is provided, in which is located a lay-boy 12. Sheets of paper that have been operated on are carried toward the layboy by a conveyor 13 that delivers into a guideway 14. This guideway directs the sheets to a second conveyor 15 that delivers the sheets into the lay-boy 12.

Beneath the conveyor 13 and at the front end of the frame 11 is shown the sheet feeder, constituting the subject-matter of the present invention.

Standards 16 are provided, on which are vertically movable sleeve 16^a, and these sleeves carry bars 17 on which is mounted a pile supporting table 18. On the upper ends of the standards 16 are heads 19, which in the present embodiment constitute parts of brackets 20 extending to the front end of the frame

11. Journaled on these brackets are stub shafts 21 carrying sprocket wheels 22. Sprocket chains 23, fastened to the opposite sides of the table, pass over the sprocket wheels 22.

The stub shafts 21 furthermore carry worm gears 24 that are in mesh with worms 25 on a cross shaft 26 journaled in the heads 19. On one end of the cross shaft is fixed a ratchet wheel 27, and journaled on the cross shaft 26 alongside the ratchet wheel is a pawl carrier 28. The pawl carrier has pivoted on its upper end a pawl 29 that engages the teeth of the ratchet wheel 27. It is also provided with a depending arm 30 having a pin 31 engaged in a slot 32 formed in one end of an operating link 33, which link has a crank connection 34 with a rotating head 35. The pawl carrier 28 furthermore has a stop finger 36 projecting from one side. A swinging detent 37, pivoted at its lower end as shown at 38, is adapted to swing into and out of the path of the stop finger 36. This detent has a link connection 39 with the crank arm 40 of a rock shaft 41 that extends across the frame. A forwardly extending arm 42 has a clamp 43 that grips the rock shaft 41 (see Fig. 4) and is thus adjustable along said rock shaft. The arm 42 is provided with a depending finger 44 that rests on the top of a pile 45 of sheets supported on the table 18.

The crank head 35 is carried by a shaft 46 that extends across the machine above the rear end of the table, and this shaft is driven by a suitable belt 47 operating around a pulley 48 that is mounted on the rear end (see Fig. 3). The shaft 46 also preferably carries a feeding device, as for example, a suction roller 49 that may correspond for example to that disclosed in my former Patent, No. 1,494,303. Directly in rear of the suction roller 49 and shaft 46 are shown feeding rollers 50 that deliver the sheets to a guideway 51 which in turn direct them to the conveyor 15.

In the operation of this device, if the top of the pile 45 is low, the finger 44 and arm 42 are of course depressed, so that the rock shaft 41 is turned to a position to withdraw the detent 37 to a position out of the path of the stop finger 36. Therefore as the shaft 46 and crank head 35 rotate and the link 33 moves forwardly, the pawl carrier 28 will swing by gravity in a direction to cause the pawl to ride over one or more teeth of the

ratchet wheel 27. When the link moves rearwardly under the action of the crank head, the pin 31 being at the front end of the slot 32, said link will swing the pawl carrier in the 5 opposite direction and thereby cause the pawl to turn the ratchet wheel. This obviously rotates the cross shaft 26 and its worms, thereby turning the stub shafts 21 in a direction to raise the sprocket chains 23 and the table 18. 10 When the top of the pile reaches the desired elevation, the arm 42 will be raised thereby through the rock shaft 41, crank 40 and link 39, swinging the detent 37 to a position beneath the stop finger 36 of the pawl carrier 15 28. The consequence is that the pawl carrier cannot gravitate as the link 33 moves forwardly, so that the pawl 29 will not override the teeth of the ratchet wheel. The operation of the pawl carrier therefore becomes ineffective 20 and yet the parts are so positioned that on each backward movement of the link 33 the pawl carrier 28 will be given a slight swinging movement sufficiently to elevate the stop finger 36 from the top of the detent, and 25 thus relieve the detent so that it can swing easily and without interference, should the top of the pile of sheets have been lowered sufficiently to remove the detent from the path of the stop finger. 30 From the foregoing, it is thought that the construction, operation and many advantages of the herein described invention will be apparent to those skilled in the art, without

further description, and it will be understood that various changes in the size, shape, proportion and minor details of construction may be resorted to without departing from the spirit or sacrificing any of the advantages of the invention. 35

What I claim, is:

1. In sheet feeding apparatus, the combination with spaced standards, of sleeves slideable on the standards, a pile supporting table carried by the sleeves and substantially centered thereon, shafts journaled above the standards and having sprocket wheels above the standards, chains operating over the sprocket wheels and extending along the standards and connected to the sleeves in line with the standards and means for simultaneously rotating the shafts and sprocket wheels.

2. In sheet feeding apparatus, the combination with spaced standards having heads on their upper ends, of sleeves slideable on the standards and carrying oppositely outstanding arms, a pile supporting table carried by the arms, shafts journaled on the tops of the heads and having sprocket wheels above the upper ends of the standards, sprocket chains passing over the wheels and connected to the sleeves, a cross shaft geared to the above shafts, and means for rotating the cross shaft.

In testimony whereof, I affix my signature.

ALBERT BROADMEYER.
